(57) **CLAIM**

The ornamental design for a wrist watch case with band, as shown and described.

DESCRIPTION

FIG. 1 is a top, right front perspective view of a wrist watch case with band showing my new design;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a right side elevational view;
 FIG. 7 is a left side elevational view thereof.
 FIG. 8 is a front elevational view thereof with the gems shown in an alternate position; and,
 FIG. 9 is a cross-sectional detail view taken along 9-9 in FIG. 5.
 The structural features depicted by broken lines in the drawings have been shown for the purpose of illustrating portions of the wrist watch case with band that form no part of the claimed design.
